Int. Cl. D9—01

U.S. Cl. D9—46

FIG. 1.

FIG. 2.

FIG. 3.

The characteristic features of our design reside in the portion shown in full lines and more specifically in the double step shape of the bail ears, the top step being provided with a stud.

We claim:

The ornamental design for a bottle, as shown and described.
